UNITED STATES PATENT OFFICE.

JAMES H. PARKER, OF MILFORD, ASSIGNOR TO JOHN L. PARKER, OF WORCESTER, MASSACHUSETTS.

MACHINE FOR COMPRESSING HEELS OF BOOTS OR SHOES.

SPECIFICATION forming part of Letters Patent No. 300,280, dated June 10, 1884.

Application filed April 14, 1884. (No model.)

To all whom it may concern:

Be it known that I, JAMES H. PARKER, a citizen of the United States, residing at Milford, in the county of Worcester and State of Massachusetts, have invented certain new and useful Improvements in Machines for Compressing Heels of Boots or Shoes, and for other Purposes; and I declare the following to be a description of my said invention sufficiently full, clear, and exact to enable others skilled in the art to which it appertains to make and use the same, reference being had to the accompanying drawings, which form a part of this specification.

The objects of my present invention are to provide a pressing-machine for compressing boot and shoe heels, embossing pieces of leather, and for other similar purposes, which machine can be conveniently and rapidly operated; to provide an automatic intermittently-acting feeding apparatus for carrying forward the material while the pressing-plates are separated; to provide means for preventing the adherence of the stock or material to the surface of the pressing or embossing plate; also, to afford facilities for adjustment of the press to different thicknesses of stock and for different degrees of feed action. These objects I attain by the mechanism illustrated and described, the particular subject-matter claimed being hereinafter definitely specified.

In the drawings, Figure 1 is a front view of my improved pressing-machine. Fig. 2 is a side view of the same. Fig. 3 is a plan view, the top part being in section below the head-block, with dotted lines indicating the relative location of the head-adjusting gears. Fig. 4 is a front view of the follower, with section of the feed-belt. Fig. 5 is a bottom view of the head-block and impressing plate or die. Fig. 6 is a sectional view on a larger scale, showing the detail of one of the discharging studs in the impressing-plate. Fig. 7 is a plan view of the feed-operating ratchet on larger scale, and Fig. 8 is a side view of the ratchet and pawl devices.

In referring to parts, A denotes the supporting-frame, composed of two side castings joined together by girts *a*, and containing suitable bearings for the crank-shaft B and oper-

ating-shaft C, which are disposed in the manner illustrated. Shaft C is provided with tight and loose pulleys C' for the driving-belt, and with a pinion, C'', that meshes with and operates the gear B' on the crank-shaft B. 55

D D indicate the standards or strain-rods, supported in upright position in sockets formed through the frame-castings, and retained by set-screws *d d*, or in other suitable manner. 60

E denotes the head-block, G the foot-block, and F the movable presser or follower, which latter is worked up and down by the knuckle-joint arms H H', respectively seated and pivoted on the foot-block G and follower F, and connected at their knuckle-joint to an arm or pitman, I, that extends to and is operated by the crank *b* of the shaft B, so that the arms H H' are expanded and contracted at each revolution of said shaft, thereby reciprocating the follower F and closing and opening the pressing-matrix. The foot-block G is arranged across the lower part of the frame on the rods D, and is held by nuts *g* on the ends of said rods, as shown. The top ends of the rods D 75 are screw-threaded, and the head-block E is sustained thereon by suitable hangers, *e*, in connection with geared nuts E', fitted on said screw-threads, and by means of which said head-block may be adjusted up and down the rods, as desired. The several nuts B' are 80 geared to a common central wheel, E'', by means of which all of the nuts E' can be turned in unison when effecting the adjustment of the head. 85

K indicates an endless belt, apron, or traveling feed-bed supported on pulleys or rolls K' and K'' at front and rear of the machine. Said rolls are mounted in bearings on brackets attached to the follower F, so that the feed-bed moves up and down with said follower. The upper part of said follower may be furnished with a slightly yielding cushion or plate, L, made of hard felt or other suitable substance that will give a strong and sufficient support for impressing the work, but which will yield under excessive pressure, so as to prevent breaking the press in case of over-sized or very thick material. The upper part of the traveling feed-bed K passes across and 90 95 100

rests upon the top of said cushion-plate L. The lower part of said bed K passes through an opening, f, arranged for that purpose centrally in the follower F. The bearings of the bed-supporting rolls are adjustable, so that proper tension can be given to the apron-belt K.

The journal of the rear roll, K², is extended beyond its bearing, and is furnished with a gear and ratchet mechanism, N, which is connected for operation by a rod, M, to a crank, M', on the shaft B, and by means of such mechanism the traveling feed-bed or apron-belt K is automatically moved with an intermittent action for carrying the articles to be pressed into position beneath the impressing-plate while the follower is depressed and the press is open. This ratchet mechanism is made substantially as shown in Figs. 7 and 8. A gear, N', having a flange or plate, N², fixed to its side, is arranged to revolve loose on the roll-shaft K. A ratchet-wheel, N³, is keyed on said shaft in position to be engaged by a pawl, n, pivoted on the plate N², and pressed down by a spring, n⁴, for taking hold on said wheel N³ only in one direction. The gear N' is rotated alternately in opposite directions by the action of the reciprocating rack m on the crank-rod M. The rack is confined to the gear by a guide, m', that runs in a groove in the hub of the gear, as shown. The reciprocative action of the follower F and rack m, transmitted through and converted by the ratchet mechanism N, effects the automatic intermittent movement of the feed-belt K, and the parts are so arranged and adjusted that such feeding movement takes place at the proper interval of time, alternating with the action of the pressing devices. The cranks M' may be adjusted for giving a greater or less movement to the feeding mechanism, as may be required for different classes of work.

P indicates the impressing plate or die, which is secured to the under side of the head-block E, to give the form or working surface for flattening, shaping, or impressing the material or article treated. The face of the plate P may be made either plain, indented, engraved, or otherwise fitted, as required, for impressing upon the work such form, finish, or ornamentation as may be desired.

To prevent adherence of the material acted upon to the surface of the plate P, I employ a series of small spring-studs, S, arranged at intervals in the body of the plate, with their ends projecting from the surface, as indicated. Said studs may be made as shown in Fig. 6, the head of the stud and a pressure-spring, s', being let into a recess formed in the plate P, and loosely confined therein by a tubular screw-threaded plug, P', in such manner that when the pressure is applied the stud S is forced up into the plate, so that its end is flush with the surface of the plate, and when the pressure is taken off the spring s' projects the stud in the manner indicated, and forces any adhering material or article from the surface,

so that it will be discharged from the press by the movement of the belt or apron K. The bolt t, which connects the plate P to the head, 70 serves as a center for the adjusting-gear E', and the hand-nut V upon said bolt serves for clamping both the plate P and the gear E' in position. Impressing-plates P of different form or with differently-ornamented surfaces 75 can be used interchangeably in the machine, as desired, for different kinds, sizes, or patterns of work, and the machine can be employed for compressing heels, stamping or embossing pieces of leather, and for other useful purposes, thus making a very convenient and desirable mechanism.

In the operation of my improved pressing-machine the heels or other articles to be compressed, embossed, or stamped are laid upon 85 the traveling apron or bed K at the front of the pressers. The intermittent movement of the apron carries them beneath the plate P, while the follower F is depressed. The feed-apron K then stops, while the follower F is elevated 90 to give the impression, and as the follower is again depressed the feed-apron again moves forward, carrying the said articles to the rear, at the same time bringing the next lay of articles into position to be acted upon by the follower, and in like manner continuing while the machine is in operation.

What I claim as of my invention, and desire to secure by Letters Patent, is—

1. The combination of the frame A, the standard-rods D, supported therein, the head-block E, the foot-block G, the follower F, the knuckle-joint arms H H', the connection I, crank-shaft B, and operating-shaft C, with gears B' C', and pulleys C', said parts being 100 arranged and operating in the manner set forth.

2. The combination, with the follower and press-head, of an endless traveling feed-belt passing through the follower, and having an 110 automatic intermittent motion imparted thereto by mechanism substantially as described, for the purposes set forth.

3. In a machine for pressing or embossing articles of leather, the combination of a head-block supporting an impressing plate or die, a reciprocating pressing-follower carrying an intermittently-acting feed-apron, and a ratchet device and connecting-rod for automatically operating said feed-apron, alternating 115 with the action of said pressing-follower, substantially as set forth.

4. The combination of the follower F, the endless apron K, the supporting-rolls K' K², mounted in bearings attached to said follower, 125 the ratchet mechanism N, mounted on the roll-shaft, the actuating-rod M, and crank M', substantially as set forth.

5. The combination, with the reciprocating follower F, endless traveling feed-belt K, and head-block E, of the removable impression-plate P, for the purpose set forth.

6. The combination, with the reciprocating follower F and head-block E, of an impress-

- ing-plate provided with a series of discharging-studs, substantially as and for the purpose set forth.
7. The combination, with the impressing-plate, of the studs S and springs s', confined in recesses formed in said plate, and adapted for action substantially as described.
8. The combination, with the follower F, feed-bed apron K, head-block E, and die or plate P, of the felt or yielding cushion L, substantially as and for the purpose set forth.
9. The combination of the stationary foot-block G, the rods D, the reciprocating follower carrying the feed-belt K, the operating-arms H H', and the adjustable head-block E with geared nuts E' and operating-gear E², substantially as set forth.
10. The combination, as described, with the feed-belt, operating-roll K², and crank-shaft B, of the ratchet N², pawl n, flanged gear N', 20 rack m, guide m', connecting-rod M, and adjustable crank M', for the purposes set forth.
11. The combination, with the head-block E, the adjusting-gear E², and the impressing-plate P, of the bolt t and hand-nut V, said bolt and nut being adapted for securing said plate and clamping said gear, as hereinbefore described.
12. The follower-block provided with a central opening or slot, as f, in combination with the endless feed-apron and knuckle-joint-operating arm, as set forth.

Witness my hand this 7th day of April, A. D. 1884.

JAMES H. PARKER.
